FISHING LURE

David L. Goforth, 613 W. Kemp Road,
Greensboro, N.C. 27401

Filed Dec. 28, 1970, Ser. No. 26,657

Term of patent 14 years

Int. Cl. D22—05

U.S. Cl. D22—27

FIG. 1

FIG. 2

FIG. 4

FIG. 3

FIG. 1 is a bottom plan view of a fishing lure showing my new design;

FIG. 2 is a side elevational view of FIG. 1;

FIG. 3 is a front elevational view of the lure of FIG. 2;

FIG. 4 is a fragmentary view of the lure taken from the right side of FIG. 2;

FIG. 5 is a top plan view of a modified embodiment of the fishing lure shown in FIG. 1;

FIG. 6 is a side elevational view; and

FIG. 7 is a front elevational view.

I claim:

The ornamental design for a fishing lure, as shown and described.
